UNITED STATES PATENT OFFICE

SYLVANUS A. REED, OF NEW YORK, N. Y., ASSIGNOR TO THE REED PROPELLER COMPANY, INC., A CORPORATION OF NEW YORK

AERONAUTICAL PROPELLER

Application filed October 29, 1929. Serial No. 403,164.

My invention relates to aeronautical propellers and is an improvement on those types of propellers described in my U. S. patents numbered respectively 1,463,556, 1,518,410, and 1,542,412. More particularly the invention has reference to a composite propeller, preferably of a heavy metal having, throughout its inner portion, a light metal reinforcing or strength giving core or hub. The term "inner portion" is used to designate the propeller part substantially within one-half the blade length, whereas the term "outer portion" is used to designate the remaining outer part thereof.

10 The principal stresses experienced by a propeller are centrifugal, which centrifugal stresses I will call C; bending, due to thrust and the torque of the engine, which bending stresses I will call B; and torsional, tending 20 to change the blade angles, which torsional stresses I will call T.

In my improved type composite propeller, I prefer to make the dimensions of the propeller itself inherently adequate to sustain 25 unaided all of the stresses C, as well as all of the stresses B and T which affect the outer portions, but inherently inadequate to sustain unaided, the stresses B and T in the inner portions. Moreover, I prefer to make the 30 propeller in a single piece from tip to tip with thin sharp outer blade portions and of rolled forged steel.

The reinforcing part of the composite propeller consists of a hub or core member with 35 blade extensions overlapping the inner portions of the propeller proper and of dimensions inherently adequate to sustain its own stresses C and also to sustain the stresses 40 B and T of the propeller blades as well as of itself. Preferably such hub or core portion is made in one piece halves of a strong forged light alloy such as duralumin, and the blade extensions are fastened to the propeller blades by bolts or rivets passing thru 45 elongated holes or slots extending lengthwise the propeller axis.

Referring to the drawings, wherein like reference characters denote like or corresponding parts,

Fig. 1 is a side or edge view of the propeller;

Fig. 2 is a plan view;

Fig. 3 is a plan view of the blank or slab from which the propeller proper is shaped;

Fig. 4 is a multiple cross-section showing the construction of the propeller at different points throughout its length, and

Fig. 5 is a side or edge view of one of the halves of the hub or core.

In Figs. 1 and 2, the thin solid steel blades of the propeller are designated as 1 and 2, whereas 3 and 3a designate twin hubs each having integral blade extensions 4, 4a, 5 and 5a. The parts 3, 4, and 5 on the one hand and the parts 3a, 4a, and 5a, on the other, are each preferably made integral and of forged duralumin. 6 and 6a are shaft holes splined or keyed to secure the propeller to an aircraft motor shaft extension. 7, 7, 7, 7, are 70 bolts for fastening the hub blades or extensions to the propeller blades 1 and 2.

The one piece steel slab from which the blades 1 and 2 are formed is best illustrated in Fig. 3. Throughout its center portion, and 75 hence throughout the inner portions of the blade, said slab is excavated as at 8 to very appreciably reduce the mass of material. At the ends of the excavation or orifice 8 channels 9 are provided. These channels, which 80 are provided on opposite faces of the slab, admit of the close fitting engagement of the hub flanges to the end that the composite inner blade ends may have a single and efficient aerofoil section. Also, as will be noted, the 85 steel slab, throughout its central region, has maximum peripheral dimension consistent with the retention of adequate cross-sectional area to sustain the centrifugal stresses.

The sections of Fig. 4, reading from left 90 to right, show the construction of the propeller at the various points indicated by the dotted lines a—a, b—b, c—c, and d—d, respectively of Fig. 2. The holes for the bolts 7, 7, 7, 7, are slotted in the direction of the 95 blade axis in order to prevent the hub flange extensions 4, 4a, 5, and 5a from sustaining any of the centrifugal stresses of the blades. In shaping the flange extensions care should be exercised to provide, in the finished prod-

uct, a composite propeller of favorable blade profile at all stations or points throughout its length. By relieving the propeller proper from the burden of sustaining its own stresses B and T I am able to dispense with considerable mass in the inner portion of the blades and thus may very materially reduce the over-all weight.

With a composite construction such as 10 herein suggested, it is only necessary to retain in the inner part of the propeller sufficient cross-section at all radii to sustain the stresses C with a proper safety factor. The hub and flange extensions require, in 15 order to meet the stresses B and T, ample over-all area rather than ample section, therefore the extensions, if desired, may be hollowed out in any convenient manner to reduce weight. A propeller thus characterized 20 has practically all the merits of a single piece solid metal propeller with probably a considerable saving in cost and without materially exceeding the weight of a similar propeller of strong light alloy.

25 In my U. S. Patent #1,463,556 I proposed hub blocks of light metal which assist in maintaining the central bends of the propeller, but such hub or hub blocks have no extensions to support the blades throughout 30 their inner portions. Also, in my U. S. Patents 1,518,410 and 1,542,412, while I described a hub with flanges twisted to conform to the blades and attached thereto for transmission of thrust and engine power, such hub 35 flanges do not assist in retaining the blade angles of the propeller against torsional stresses.

While I have described my invention in detail in its present preferred embodiment, it 40 will be obvious to those skilled in the art after understanding my invention, that various changes and modifications may be made therein without departing from the spirit or scope thereof. I aim in the appended claims 45 to cover all such modifications and changes.

What I claim is:

1. In an aeronautical propeller, blades formed from a single piece of strong forged relatively heavy metal continuous from tip to tip with the outer portions thereof thin and sharp and having at all radii cross-sections inherently adequate to resist both rupture and deformation, said blades, in the vicinity of the center of rotation of the propeller, having sufficient cross-sectional area to sustain unaided the centrifugal stresses the insufficient to sustain unaided angle changing stresses; a hub and core of strong the relatively light weight metal for reinforcing said inner blade portion, said hub and core being formed with integral radial elongated flange extensions having inherently adequate torsional rigidity to give to said inner portions of the blade the necessary factor of safety against angle changing stresses;

and means for fastening said flange extensions to the propeller blades.

2. In an aeronautical propeller, centrally excavated, and hence materially lightened blades formed from a single length of strong forged relatively heavy metal continuous from tip to tip with the outer portions thereof thin and sharp and having at all radii cross-sections inherently adequate to resist both rupture and deformation, said blades 75 in the vicinity of said excavations having sufficient cross-sectional area to sustain unaided the centrifugal stresses the insufficient to sustain unaided the angle changing stresses; a hub and core of strong the relatively light weight metal for reinforcing said excavated blade portion 80 blade portion, said hub and core being formed with integral radial elongated flange extensions having inherently adequate torsional rigidity to give said excavated blade portion 85 the necessary factor of safety against angle changing stresses; and means for fastening said flange extensions to the propeller blades.

3. In an aeronautical propeller, centrally excavated, and hence materially lightened blades formed from a single length of strong forged relatively heavy metal continuous from tip to tip with the outer portions thereof thin and sharp and having at all radii cross-sections inherently adequate to resist both 95 rupture and deformation, said blades in the vicinity of said excavations having sufficient cross-sectional area to sustain unaided the centrifugal stresses the insufficient to sustain unaided the angle changing stresses; a hub and core of strong the relatively light weight metal for reinforcing said excavated blade portion 100 blade portion, said hub and core being formed with integral radial elongated flange extensions having inherently adequate torsional rigidity to give said excavated blade portion 105 the necessary factor of safety against angle changing stresses; and means passing thru holes slotted in a radial direction for fastening said flange extensions to the propeller blades.

4. In a composite aeronautical propeller, blades formed from a single length of strong forged relatively heavy metal continuous from tip to tip with the outer portions thereof thin and sharp and having at all radii cross-sections inherently adequate to resist both 115 rupture and deformation, and with the inner portions thereof excavated to obtain a maximum of weight reduction consistent with retaining in said inner blade portions sufficient cross-sectional area to sustain unaided the centrifugal stresses incurred during use, the insufficient in cross-sectional area to sustain unaided the torsional and bending 120 stresses imposed on the blades; a hub and core of strong the relatively light weight metal for reinforcing said inner blade portions, said hub and core being formed with integral radial elongated flange extensions having in- 125 130

- herently adequate torsional rigidity to give to said inner blade portions the necessary factor of safety against angle changing stresses, and means attaching the propeller blades to said hub and core member, said means being carried thru holes slotted in a radial direction and disposed to relieve the attaching means from centrifugal stresses.
5. In an aeronautical propeller, blades formed from a single excavated metal piece continuous from tip to tip and shaped at all radii throughout the outer portions of the respective blade lengths to favorable blade profiles, and a radially elongated hub and core portion substantially co-extensive with said excavated blade portion and to which the blades are fastened for reinforcement against angle changing stresses.
10. In an aeronautical propeller, blades formed from a single excavated metal piece continuous from tip to tip and shaped at all radii throughout the outer portions of the respective blade lengths to favorable blade profiles, and a radially elongated hub and core portion substantially co-extensive with said excavated blade portion and to which and with which the inner blade portions are fastened and shaped to favorable blade profiles respectively.
15. In an aeronautical propeller, blades of a relatively heavy metal excavated throughout a substantial portion of their respective lengths and to an extent necessitating the employment of a reinforcing means for adequately sustaining the angle changing stresses encountered in actual service, and a combined hub and core member of relatively light metal fastened to the respective blades and elongated radially to reinforce the excavated portions thereof, each said blade, throughout the inner portion of its length, and in conjunction with said elongated core member, and throughout the outer portion of its length, independently of said elongated core member, being shaped to favorable blade profiles at all radii.
20. In a composite metal aeronautical propeller, a propeller blade including a metal piece continuous from root to tip, said metal piece, in the vicinity of said blade root and for a substantial portion of the blade length, being excavated to an extent necessitating the employment of a reinforcing means, not for the purpose of sustaining any substantial portion of the centrifugal stresses, but for the purpose of sustaining a substantial portion of the angle changing stresses encountered in actual use, and means associated with said excavated blade portion and fastened to said blade and of a lighter material than said blade, said means providing the necessary reinforcement where reinforcement is required and being faired with the continuous metal piece to approximately
25. aerofoil profile throughout a substantial portion of said reinforcement.
- In testimony whereof I hereunto affix my signature.
